CLAIM

The ornamental design for a display screen with graphical user interface, as shown and described.

DESCRIPTION

FIG. 1 is a front view of the first image of a display screen with graphical user interface showing a first embodiment of our new design;

FIG. 2 is a front view of a second image of the first embodiment;

FIG. 3 is a front view of a third image of the first embodiment; FIG. 4 is a front view of a fourth image of the first embodiment;

FIG. 5 is a front view of a fifth image of the first embodiment; FIG. 6 is a front view of the first image of a display screen with graphical user interface showing a second embodiment of our new design;

FIG. 7 is a front view of a second image of the second embodiment;

FIG. 8 is a front view of a third image of the second embodiment;

FIG. 9 is a front view of a fourth image of the second embodiment; and,

FIG. 10 is a front view of a fifth image of the second embodiment.

The broken line drawing of a display screen in all views illustrates unclaimed environment and forms no part of the claimed design. The broken line showing the remainder of the image in all views illustrates unclaimed portions of the design and forms no part thereof.

In FIGS. 1-5 of the first embodiment, the circle-ring-shaped stripe, continuous-line-shaped stripes and discontinuous-line-shaped stripes convey the impression of a translucent surface, and the round spots do not convey the impression of a translucent surface. In FIGS. 6-10 of the second embodiment, the circle-ring-shaped stripe, continuous-line-shaped stripes, discontinuous-line-shaped stripes, and the round spots do not convey the impression of a translucent surface. The appearance of the transitional image sequentially transitions between the images shown in FIGS. 1-5 of the first embodiment and FIGS. 6-10 of the second embodiment. The process or period in which one image transitions to another image forms no part of the claimed design.
